Primary Examiner — Paula Allen Greene(74) *Attorney, Agent, or Firm* — ALONZO &
ASSOCIATES; Arlyn Alonzo(57) **CLAIM**

The ornamental design for a headphone/headset, as shown and described.

DESCRIPTION

FIG. 1 is a perspective view of a headphone/headset showing the new design;

FIG. 2 is a front view thereof.

FIG. 3 is a back view thereof.

FIG. 4 is a left view thereof.

FIG. 5 is a right view thereof.

FIG. 6 is a bottom view thereof; and,

FIG. 7 is a top view thereof.

The headphone/headset may be used for listening to music and/or audio signals from a transmitting device. The headphone/headset may be a wired or a wireless device.

1 Claim, 4 Drawing Sheets(56)
